INVENTOR

Carl Otto

BY
N. J. Bissell

ATTORNEY

UNITED STATES PATENT OFFICE.

CARL OTTO, OF ESSEN-RUHR, GERMANY.

COKE OVEN.

Application filed April 9, 1927, Serial No. 182,342, and in Germany April 3, 1926.

The top walls of coke ovens usually are provided with inspection holes. These holes allow the operator to watch the stages and conditions of the combustion taking place in the individual heating flues of the oven, to adjust the damper bricks located on the top end of said flues, and, further, to clean the gas nozzles located on the floor end of the flues by pushing a stoker or the like through them from above, when these nozzles have become stopped up. My invention relates to a construction of these well-known inspection holes. According to my invention the openings in the oven top are so constructed that they admit an exchange from the top, of said heating gas nozzles on the lower end of the flues. To this end, an opening is provided in the masonry of the top and is filled by a removable brick having a passage aligned with the opening loosely put therein, so that an inspection hole exists even when said brick has been put in, whilst the brick has to be withdrawn when the nozzles are to be exchanged.

In order to allow of my invention to be more easily understood, a preferred embodiment of same in a coke oven having vertical heating walls is illustrated in the drawing which accompanies and forms part of this specification. In this drawing:

Fig. 1 is a longitudinal section through a portion of a heating wall of a coke oven, and

Fig. 2 is a partial cross section through the oven battery. . . .

As to be seen from Fig. 1, each heating wall is subdivided in the known manner so as to form individual vertical heating flues *a*, on the bottom end of which each a heating gas supply passage *b* opens thereinto. A nozzle *k* is provided on the top of each passage *b*. An opening *d* is arranged in the masonry of the top *c* of the oven battery above each heating flue *a* and is covered each by a removable cover brick *e*. The openings *d* have each an

annular shoulder *d*¹ on which a removable filling brick *f* having a central inspection passage *f*¹, may be put. The cover bricks *e* likewise have passages *e*¹ situated vertically above the passages *f*¹ of the bricks *f* and adapted to be closed by a stopper *g*. As to be seen from the drawing, the filling bricks *f* need not completely fill the whole height of the opening *d*, the height of bricks *f* being, on the contrary, preferably so determined, that the bricks afford a satisfying isolation against the heat radiating from the heating

flues in upward direction and loosely filling the opening in the top oven. A brick or iron fitting tube *h* may be interposed between brick *e* and brick *f*, and the space existing between this tube *h* and the wall of the opening *d* may be filled with an asbestos mass or the like, if required. The opening in the oven top, the passage in the filling brick *f*, the fitting tube and the cover brick *e*, communicate with and are aligned with the respective heating flues. For the purposes hereinbefore explained, of the well-known inspection holes, with the oven of my invention nothing is required but the removal of the stoppers *g*. Furthermore, besides this, an exchange of the nozzle bricks *k* from the top is rendered possible in the simplest manner by merely removing, after the withdrawal of the cover bricks *e*, the tube *h* and brick *f* from the opening *d* in consideration, so that the nozzle *k* in question may be withdrawn from above in a very easy manner.

What I claim as my invention and desire to secure by Letters-Patent, is:—

1. A coke oven comprising a vertical heating flue and a removable burner nozzle in the same, the top of said oven having an opening therethrough communicating with and in alinement with said flue and of such diameter as to permit the removal of the burner nozzle through said opening, a removable cover brick closing said opening, the latter having an internal shoulder near its lower end, a removable filler brick loosely filling said opening and resting on said shoulder, both of the bricks being provided with sight holes in alinement with said flue, and a tubular member extending between said bricks and of substantially smaller diameter than said opening, whereby a space is provided around said member to receive a heat resistant and insulating packing material, the aperture through said tubular member being in alinement with said holes.

2. A coke oven comprising vertical heating flues and removable burner nozzles in the lower ends of said flues, the oven top having openings therethrough communicating with and in alinement with the flues and of sufficient diameter to permit the removal of the nozzles through the said openings, removable cover bricks closing said openings, removable filler bricks loosely fitted in the lower part of said openings, all of said bricks having central sight holes, and a tubular member in each opening extending between the filler and

cover bricks therein and of substantially smaller diameter than the opening, whereby a space is left around said member to receive heat resistant and insulating material, the aperture through each of said tubular members being in alinement with the holes in the cover brick and filler brick in the same opening therewith.

3. In a coke oven having vertical openings
- 10 through its top, vertical heating flues directly beneath said openings, and communicating therewith, a removable burner nozzle in each flue, said openings being of a size to enable the burner nozzles to pass therethrough and the
  - 15 lower portion of each opening having an internal shoulder, a removable filler brick loosely fitted in each opening and resting on

said shoulder, a removable cover brick closing each opening at its top, both of the bricks being centrally perforated to provide a peep hole, plugs for closing the holes in the cover bricks, a tubular member of substantially less diameter than the openings extending between the filler brick and the cover brick in each of said openings, and a packing of asbestos filling the annular space between the tubular member and the wall of the opening over each flue, the aperture through each of said tubular members being in alinement with the holes in the cover brick and the filler brick in the same opening therewith.

In testimony whereof, I have signed my name to this specification.

CARL OTTO.
